UNITED STATES PATENT OFFICE.

LUCIAN B. NASH AND ROBERT E. MOORE, OF CHICAGO, ILLINOIS.

MECHANISM FOR PULVERIZING AND FEEDING FUEL.

SPECIFICATION forming part of Letters Patent No. 740,167, dated September 29, 1903.

Application filed May 26, 1902. Serial No. 108,902. (No model.)

To all whom it may concern:

Be it known that we, LUCIAN B. NASH and ROBERT E. MOORE, of Chicago, in the county of Cook and State of Illinois, have invented 5 certain new and useful Improvements in Mechanism for Pulverizing and Feeding Fuel; and we do hereby declare that the following is a full, clear, and exact description thereof, reference being had to the accompanying drawings, and to the letters of reference marked thereon, which form a part of this specification.

This invention relates to improvements in mechanism for pulverizing fuel, such as coal, 15 and feeding the pulverized fuel to furnaces; and the invention consists in the matters hereinafter set forth, and more particularly pointed out in the appended claims.

In the drawings, Figure 1 is a front elevation of a boiler-furnace provided with our improved fuel-feeding devices. Fig. 2 is a transverse vertical section with parts broken away, showing one set of pulverizing devices and its associated feeding device. Fig. 3 is a partial 25 longitudinal section taken on line 3-3 of Fig. 2. Fig. 4 is a plan section taken on line 4-4 of Fig. 3.

As shown in the drawings, A designates the front wall of the furnace; B, a hopper for the 30 fuel; C, a pipe leading from a source supplying coal and having at its lower end a flaring discharge end C', which fits over the top of the hopper; D, a plurality of fuel-feeding devices which communicate with the lower 35 converging side of the hopper and also with the furnace through the medium of fuel-delivery pipes D'; E, an air-supply pipe communicating with the fuel-feeding devices D through the medium of pipes e; and F, a chamber which contains air or other feeding fluid 40 under pressure and is connected by a pipe f with the pipe E, said pipe f having a regulating-valve f'. The pipe E may be connected directly with an air-pump for affording the 45 desired pressure of the feeding medium or may be connected with a source supplying steam under pressure if it be desired to use steam as the feeding medium.

The hopper B is made of elongated form and 50 extends practically from one side of the furnace to the other and the feeding devices communicate with and receive fuel from the lower

converging side of the hopper. The feeding devices embrace chambered castings D², the interior chambers D³ of which receive the pulverized fuel and from whence it is fed to the furnace through the fuel-delivery pipe D'. Said fuel-feeding devices embrace also mechanism for delivering a feeding medium, such as air or steam, to the chamber D³ and pipe 55 D', as will hereinafter more fully appear. Said chambered castings of the feeding devices may be separately connected with the hopper; but I have shown all of said devices embodied in a single casting and provided at 60 its upper side with an elongated flaring mouth, which fits within the lower margin of the converging side walls b of the hopper and attached thereto by bolts or like fastening devices. The end walls of said hopper are made 65 somewhat heavier than the side walls and fit at their lower margins against the end walls of the casting containing the feeding devices. The end walls of the hopper will desirably be made of cast-iron plates and the side walls will 70 be made of sheet-metal plates.

Located at the lower end of the hopper and between the same and the feeding-chamber D³ are a plurality of pulverizing devices which receive the fuel from the hopper and crush or 75 pulverize the same to the desired degree of fineness and discharge said pulverized fuel into the chamber D³ of the feeding device, from whence said pulverized fuel is delivered through the pipes D' to the furnace. Said pulverizing devices, as herein shown, consist each of two flat-faced disks or burs F' F², having roughened cooperating faces. One of said burs—the bur F², as herein shown—is rotary and the other is stationary. The rotary burs are affixed to 80 horizontal transverse shafts F³, which are rotatively mounted in bearings in the casting D² in the manner shown in Fig. 4. As therein shown, each shaft is mounted at one end in an integral bearing sleeve or boss d and at its 85 other side in a tubular nut d', which is externally screw-threaded and engages an internally-screw-threaded boss d² in a removable plate d³, secured at its upper end by bolts d⁴ to the casting D² and at its lower end by bolts d⁵ to said casting in the region of the fuel-delivery pipe D'. The forward ends of the shafts F³ extend beyond their bearings d and are 90 provided at their outer ends with beveled

- gear-wheels F^4 , which mesh with like gear-wheels G , which are affixed to a rotary shaft G' , mounted in bearings d^6 , extending outwardly from the hopper, as shown in Fig. 1.
- 5 The gear-wheels G are loosely mounted on the shaft G' and are adapted to be operatively connected with and disconnected from the shaft by means of clutch mechanisms, whereby the operations of the rotary burs may be controlled. Said clutches, as herein shown, consist of spur-clutches H of a familiar construction and are provided with operating-levers H' , which are pivoted to the adjacent wall of the hopper and to the movable parts 10 of the clutches. Said rotative burs F^2 are affixed by the shaft F^3 by means of keys or splines f^2 , as shown in Fig. 2, whereby said burs rotate with the shaft, but may be moved toward or away from the stationary burs in 15 a manner hereinafter to be described. The rotary burs are provided with hubs f^3 , which engage the inner ends of the adjusting-nuts d' , and the keys or splines f^2 of the hubs f^3 engage keyways in the shafts, as shown in 20 Fig. 2, said keyways extending to the outer ends of the shafts to permit the burs F^2 to be removed from the shafts. The stationary burs are provided with hubs F^4 , having angular exterior surfaces fitting corresponding sockets 25 in projections d^7 , extending inwardly from the casting D^2 , as shown in Figs. 3 and 4, and said hubs are provided with cylindric bores through which the shafts F^3 extend and in which said shafts rotate. The stationary burs 30 contact at their central parts with said projections d^7 and bear near their margins against annular seats or shoulders d^8 , formed on said casting D^2 , said projections d^7 and annular shoulders d^8 constituting a suitable backing 35 to support the stationary burs during the operation of the burs.
- The rotary bur of each pair is adjusted with respect to the stationary bur by means of the screw-headed nut d' , before mentioned, 40 said nut being turned inwardly to move the rotary bur toward the stationary bur and outwardly to permit the rotary bur to be moved away from the stationary bur. When the nut d' is moved outwardly away from the 45 stationary bur, the coal entering between the burs presses the rotary bur outwardly, with its hub f^3 abutting against the inner end of the nut d' .
- Means are herein shown for simultaneously 50 moving all of the rotary burs F^2 toward and from the stationary burs for the purpose of varying the fineness of the coal reduced between the same. Said means consists, as herein shown, of a horizontal shaft I , which 55 is located over said adjusting-nuts d' and extends from one end to the other of the device. Said shaft I is provided with screw-threaded sections I' , which are adapted to mesh with worm-gears formed on the outer ends of the 60 nuts d' in the manner clearly shown in Figs. 2 and 4. Said shaft I is mounted in bearings i , extending rearwardly from the hop-

per, and is provided at one end with a hand-wheel I^2 , by which the shaft is rotated to turn the nuts d' inwardly or outwardly, as desired. 70

The stationary burs are cut away at their upper parts to provide openings F^5 , through which the coal passes from the hopper to the spaces between the burs. The lower side of the hopper is shown as provided with oppositely-inclined parts $d^5 d^5$, which converge toward the openings F^5 of the stationary burs and are arranged to direct the coal from the hopper to said openings, as clearly shown in Fig. 3.

The fuel-delivery pipes D' , through which the chambers D^3 communicate with the furnace, enter the rear walls of said chambers, and the walls of said chambers are provided in alignment with said pipes D' with screw-threaded openings which receive the air-pipes e , which communicate with the main air-pipe E . The bores of said air-pipes e at their inner ends are screw-threaded and receive short air-tubes J , which extend at their forward ends through the chamber D^8 and a short distance into the fuel-delivery pipes D' . The outer ends of said air-tubes J are provided around the bores thereof with conical seats j , and said seats are adapted to be engaged by conical valves or closures k , which are attached to or formed on the ends of valve-stems K . Said valve-stems extend outwardly transversely through the pipe E and have screw-threaded engagement with the reduced outer ends of the pipes e , whereby rotary movement of the stems moves the closures toward and from their seats. Said valve-stems extend through stuffing-boxes e' at the outer ends of the air-pipes e and are provided at their outer ends with hand-wheels K' , by which 105 said spindles are rotated. The air or other fuel-feeding medium employed passes from the pipe E through the valves, embracing the seats j and closures k , and thence through the tubes H , and the passage of said feeding medium into and through the pipes D' creates a 110 vacuum in the chambers D^3 and draws the pulverized fuel which drops into said chambers from the spaces between the burs $F^2 F^2$ into and through the pipe D' and delivers 115 the pulverized fuel and commingled fuel-feeding medium into the furnace. The supply of air may be accurately regulated with respect to the quantity of pulverized fuel used by means of the air-valves described, or such supply of air may be cut off entirely. The supply of fuel delivered to the feeding-chambers D^3 from the burs may be also regulated by 120 regulating the speed of the rotary burs.

It may be desirable in some instances to cut 125 out one set of pulverizing and feeding devices from the operative series, and this may be accomplished by disengaging through the clutch mechanism described the bur-shafts from the main driving-shaft and by also cutting off the air to the feed-chamber associated therewith through the medium of the air-valve described.

Before stopping the operation of one or

more of the burs it is very desirable that all of the fuel fed to the space between the burs be cleared therefrom before operation of the burs is stopped. For this purpose we have 5 shown a valve or gate located between the hopper and the burs so as to cut off the hopper from the burs when one or more of the pairs of burs are to be stopped. After the valve has been closed the operation of the 10 burs is continued until the burs are cleared. In starting the burs again, rotation of the burs is started before the valves are opened, so that the burs start freely and without exerting an excessive strain on the mechanism, 15 as would occur if the spaces between the burs be filled upon resumption of the operation thereof. Said valves consist of flat plates L, which slide in ways or grooves in the tops of the inclined portions d⁵ at the bottom 20 of the hopper, as clearly shown in Figs. 2 and 3. Said valves are provided with operating-handles, which extend outwardly through the hopper. Said valves also serve to regulate the amount of coal to be delivered to the 25 grinders, and by regulation thereof only the amount of coal which it is desired to feed to the furnace need be pulverized. Moreover, by reason of the independent adjustment of the valves certain of the grinders may 30 receive more coal than others, whereby a variable distribution of the coal may be afforded, as best practice may dictate.

In the mechanism so far described it has been assumed that the coal fed to the pulverizing-burs is of uniform fineness and preferably of the size known as "pea-coal." We 35 have shown, however, means located in the hopper for reducing larger particles of coal to smaller uniform-sized particles, whereby 40 the use of the device need not be limited to a certain size of coal. Said means, as herein shown, consists of two parallel horizontal oppositely-rotating rollers M M, located in the hopper above the valves L and mounted in 45 suitable bearings in the end walls of the hopper. Said rollers are provided with radial crushing-arms M', as shown in Figs. 2 and 3, and the arms of one roller pass between the arms of the other roller, whereby coal passed 50 between said rollers is crushed and reduced by said interfitting radial arms. The hopper is provided on the interior walls thereof with inclined ledges B⁴ B⁴, which act to direct the coal delivered to the hopper centrally over 55 the space between said rollers. Said rollers M are provided at their ends outside of their bearings in the end walls of the hoppers with intermeshing gear-pinions m, whereby the rollers are given positive rotary movement in 60 opposite directions. Said gear-pinions are rotated through the medium of a rotative shaft N, which is driven from any suitable source of power and provided with a gear-pinion n, which meshes with one of the gear- 65 pinions m of the crusher-rollers. As herein shown, the driving-shaft G' is also driven from said shaft N, said shaft G' being pro-

vided with a gear-wheel G², which meshes with the gear-pinion m, before described. Said shaft N is adapted to be connected with driving means in such manner that the speed of the same may be varied, whereby the rotary speed of the crushing-rollers and the pulverizing-burs may be correspondingly varied. 70

The operation of the mechanism described 7 will be obvious from the foregoing, but may be briefly stated as follows: Coal is fed to the hopper B in quantities depending upon the demand made thereon by the furnace. If the preliminary crushing-rollers be employed, 80 said fuel passes between said crushing-rollers and is by the radial interacting arms thereof reduced to a size by which it may be fed to the spaces between the pulverizing-burs. The coal fed between the pulverizing-burs 85 is pulverized by the action of said burs and is discharged by the said burs, after being reduced to the required degree of fineness, into the feed-chambers D³. By reason of the vacuum existing in said chambers, effected 90 by the air-forcing devices before described, the coal dropped into said chambers is caught up by the air-currents and delivered with considerable force, depending upon the pressure used, into the furnace. It will be observed that the fuel-delivery pipes D' open 95 into the furnace at short distances apart, whereby the fuel is distributed uniformly throughout the furnace. The amount of coal fed to the furnace is regulated by the speed 100 of the crushing and pulverizing devices, and the quantity of air delivered by the air-forcing devices into the feed-chambers may be regulated to suit the demands brought upon the furnace. As before stated, one or 105 a greater number of the burs and the associated feeding devices may be cut out of the operative series, either for the purpose of regulating the feed or fuel or for the purpose of repairing the burs. When it is desired to 110 remove either of the burs, the removable plate-nut d' thereof is removed, after which the plate associated with said nut is detached from the hopper, whereupon said burs are 115 readily accessible for removal.

An important advantage of the construction described is that we are enabled to dispense with the handling of the pulverized fuel, which is necessary in constructions where the pulverized fuel is fed directly to the hopper and thence to the feeding devices, thereby obviating the disadvantage of handling the fuel in this state. A further important advantage of the relation of the pulverizing-burs to the feeding device is that the pulverized fuel as it 120 leaves said burs is taken up directly by the air or other feeding medium and is carried directly to the furnace, and no necessity arises therefore for feeding the fuel to the feeding-chambers, such as occurs if the pulverizing devices be located at a distance from the feeding devices. Moreover, by reason of the fact that the fuel in the hopper is in such 125 a state or condition that it may be readily 130

handled, (which is not true of the finely-pulverized fuel,) and that the quantity supplied to and pulverized by the grinders or pulverizing device may be regulated in accordance with the demands brought upon the furnace, and of the further fact that the fuel after it is pulverized has free and unrestricted passage to the furnace, there is no tendency of the fuel to lodge in and choke the feed chambers and passages, such as is likely to occur where a plurality of feed devices are connected with a common source supplying pulverized fuel. In the latter event should one or more of the passages become clogged or partially clogged the varied resistance to the flow of the fuel through the passages results in a non-uniform feed of the fuel to the furnace, and where an attempt is made to regulate the flow of fuel by valves the liability of such clogging is increased. The usefulness of an apparatus of the character described depends upon its capability of accurately supplying the pulverized fuel to the furnace in accordance with a desired adjustment, for the reason that the fuel immediately ignites upon its admission to the furnace and irregularities in the supply of the fuel manifests itself at once in a variable temperature of the furnace. This feature of our invention in its application to a multiple pulverizing and feeding device is of great importance, as we are thereby enabled to accurately regulate the amount of fuel fed to the furnace in accordance with the demands brought upon the furnace, and thereby maintain an even and uniform temperature in the furnace.

The use of the plurality of pulverizing devices operated from a common source of power by means constructed to separately disconnect each device from said source of power and connected severally by feed-passages with the furnace is of great importance, for the reason that when one or more of the grinding and feeding devices is thrown out of action—as, for instance, each alternate grinding and feeding device—the power necessary to operate the grinding devices is correspondingly decreased, so that it is necessary to expend only the power required to properly pulverize the fuel consumed.

An agitator may, if desired, be located below the crusher for the purpose of preventing the coal choking at the entrance to the pulverizers. The mechanism herein shown may obviously be employed in connection with any furnace, as the operation thereof may be regulated to suit the requirements of a wide range of furnaces.

The provision of the preliminary crushing-rollers is of considerable importance, as by the use of the same the apparatus is not limited to fuel reduced to a certain degree of fineness. With this construction, therefore, we are enabled to obviate the inconvenience which would arise in cases where fuel of a certain degree of fineness could not be secured, as by the construction shown we are enabled to use

fuel varying widely in respect to the size of the individual particles thereof.

A further advantage of the construction shown is the extreme simplicity of the mechanism and the employment of few parts. As a result the mechanism is not likely to get easily out of order, thereby rendering the cost of maintenance very economical.

The feeding-chambers D³ are provided in their lower walls with openings closed by screw-threaded plugs, as shown in Figs. 2 and 3, whereby the chambers may be cleaned when necessary. A further purpose of said openings is to enable the operator to readily ascertain the fineness of the fuel being pulverized, it being only necessary to remove one of the plugs to permit a sample of the fuel to drop therefrom. Such sampling of the fuel will usually be done upon starting the mechanism in operation. In this manner the operator or engineer is enabled to at all times be apprised of the condition of the fuel being consumed.

It is obvious that many changes may be made in the structural details herein shown, so far as the broader aspects of the invention are concerned, and we do not wish to be limited to such details except as hereinafter made the subject of specific claims.

We claim as our invention—

1. Mechanism for pulverizing and feeding fuel to a furnace comprising, in combination with a furnace, a plurality of pulverizing devices, a source of granular or unpulverized fuel common to and communicating directly with all of said pulverizing devices, a plurality of unrestricted passages leading from said pulverizing devices to different parts of the furnace, and means for separately and forcibly delivering the pulverized fuel from said pulverizing devices through said passages to the furnace.

2. Mechanism for pulverizing and feeding fuel to a furnace comprising, in combination with a furnace, a plurality of pulverizing devices, a source of granular or unpulverized fuel common to and communicating directly with all of said pulverizing devices, means for regulating the output of pulverized fuel from the pulverizing devices, a plurality of unrestricted passages leading from said pulverizing devices to different parts of the furnace, and means for forcibly delivering the pulverized fuel from said pulverizing devices through said passages to the furnace.

3. Mechanism for pulverizing and feeding fuel to a furnace comprising, in combination with a furnace, a plurality of pulverizing devices, a source of granular or unpulverized fuel common to and communicating directly with all of said pulverizing devices, means for separately regulating the output of the pulverized fuel from said pulverizing devices, and means for forcibly delivering the pulverized fuel from said pulverizing devices through said passages to the furnace.

4. Mechanism for pulverizing and feeding fuel to a furnace, comprising, in combination

- with a furnace, a plurality of pulverizing devices, a source of granular or unpulverized fuel common to all and communicating directly with said pulverizing devices, means 5 for regulating the output of pulverized fuel from said pulverizing devices, a plurality of unrestricted passages leading from said pulverizing devices to different parts of the furnace, means for supplying a feeding medium 10 under pressure to force the pulverized fuel through said passages to the furnace, and means for varying the force of the feeding medium.
5. Mechanism for pulverizing and feeding fuel to a furnace, comprising, in combination with a furnace, and a plurality of pulverizing devices, a source of granular or unpulverized fuel common to all and communicating directly with said pulverizing devices, means 15 for regulating the output of the pulverizing devices, a plurality of unrestricted passages leading from said pulverizing devices to different parts of the furnace, means for applying a feeding medium under pressure to the 20 several passages to force the pulverized fuel therethrough to the furnace, and means for separately varying the supply of the feeding medium.
6. Mechanism for pulverizing and feeding fuel to a furnace, comprising, in combination 25 with a furnace, a hopper, a plurality of pulverizing devices which receive fuel from said hopper, valves for regulating the supply of fuel from said hopper to said pulverizing devices, feeding devices embracing feeding-chambers communicating with the furnace through unrestricted passages, each of which receives fuel from one of the pulverizing devices, and means for supplying a feeding medium under pressure, to said chambers for 30 forcing the pulverized fuel therefrom through said passages into the furnace.
7. Mechanism for pulverizing and feeding fuel to a furnace comprising, in combination 35 with a furnace, a plurality of pulverizing devices operated from a common source of power, a source of granular or unpulverized fuel common to and communicating directly with all of said pulverizing devices, a plurality 40 of passages leading from said pulverizing devices to the furnace, means for forcibly delivering the pulverized fuel from said pulverizing devices through said passages to the furnace, and means for separately cutting
- said pulverizing devices out of the operative series.
8. Mechanism for pulverizing and feeding fuel to a furnace, comprising, in combination with a furnace, a hopper, a plurality of pulverizing devices which receive fuel directly from said hopper and are operated from a common source of power, valves between said hopper and the pulverizing devices, means for separately cutting the pulverizing devices out of the operative series, chambers which severally receive the pulverized fuel from said pulverizing devices, passages leading from said chambers to different parts of the furnace, and means for supplying a feeding medium, under pressure, to force the fuel from the chambers into the furnace.
9. Mechanism for pulverizing and feeding fuel to a furnace, comprising, in combination with a furnace, a hopper, a plurality of pulverizing devices which receive fuel from the hopper, shafts for operating said pulverizing devices, gear-wheels on said shafts, a main driving-shaft provided with gear-wheels which mesh with the gear-wheels of the shafts of the pulverizing devices, means for feeding the pulverized fuel to the furnace and means for separately disconnecting the shafts of the pulverizing devices from the main driving-shaft.
10. Mechanism for pulverizing and feeding fuel to a furnace, comprising, in combination with a furnace, a hopper, a plurality of pulverizing devices receiving fuel directly from said hopper, means for varying the output of the pulverizing devices, a chamber associated with each pulverizing device and receiving the pulverized fuel therefrom, an unrestricted passage leading from one side of each chamber to the furnace, a feeding-medium pipe entering said chamber, in alignment with the fuel-delivering pipe thereof, and means for supplying a feeding medium, under pressure, through said pipe.

In testimony that we claim the foregoing as our invention we affix our signatures, in presence of two witnesses, this 20th day of May, A. D. 1902.
